STANLEY KONAT, OF DETROIT, MICHIGAN

COMBINATION LOCK

Application filed June 23, 1930. Serial No. 462,948.

This invention relates to locks, and particularly combination locks.

An object of the invention is to equip a lock with a plurality of pivotal bolts and adapt them for control in unison through a manipulation of tumblers, according to a predetermined combination.

Another object is to so engage the door-carried and frame-carried members of a lock as to prevent their disengagement by a jimmy or the like applied between the door and frame.

A further object is to adapt a combination lock to be readily operated in the dark by causing any angular advance of the tumblers to produce a proportionate number of clicks, and to provide means for determining by sound and touch the initial point from which the combination may be worked.

Still another object is to form the face plate of a lock casing with bolt-receiving slots, whereby the bolts may swing between locked and unlocked positions, and to associate with the bolts sliding closures for said slots, preventing access to the lock mechanism through said slots.

These and various other objects the invention attains by the construction hereinafter described and illustrated in the accompanying drawings:

Fig. 1 is a fragmentary perspective view of the outer face of a door equipped with the improved lock, showing also a portion of the door frame, mounting a keeper for said lock.

Fig. 2 is a view of the lock, with the cover plate of its casing removed and the bolts in locking position.

Fig. 3 is a similar view with the bolts in unlocked position.

Fig. 4 is a cross sectional view of the improved lock, taken upon the line 4—4 of Fig. 3 and showing a portion of the door wherein the lock is mortised.

Fig. 5 is a view of the lock with the cover of its casing removed, showing the unlocking position of the bolts as established by manipulation of the tumblers, certain of the parts being in section.

Fig. 6 is a perspective view of the bolts

together with a pair of associated bell crank levers.

Fig. 7 is a perspective view of the top portion of an escutcheon plate, showing an opening therein for engagement by a stop element 55 to determine proper initial point of tumbler actuation.

Fig. 8 is a view in elevation of the tumblers of the improved lock.

Fig. 9 is an elevational view of one of a 60 set of sheet metal spacers, adapted to separate the tumblers.

Fig. 10 is a view of the lock with the casting cover, the tumblers and certain other parts removed to show a means for producing 65 clicks to indicate the angular advance of the tumblers.

Fig. 11 is an axial sectional view of the tumbler-actuating knob, showing the same under pressure to establish the proper initial, 70 tumbler-actuating position.

Fig. 12 is a sectional view taken upon the line 12—12 of Fig. 2, and primarily showing sliding closures for the face-plate slots which accommodate the bolts.

Fig. 13 is a sectional view of the tumbler-actuating knob, taken upon the line 13—13 of Fig. 4.

Fig. 14 is a fragmentary section of said knob and the adjacent escutcheon plate, taken 80 on the line 14—14 of Fig. 13.

Fig. 15 is a perspective view of the inside door handle stem.

In these views, the reference character 1 designates a lock casing attached to the rear 85 of a face plate 2 and mortised into a door 2a, as is common practice. One of the side walls 3 of said casing forms a cover plate removable for access to the lock mechanism, and is normally attached to the casing by screws 4 90 or the like.

A pair of similar bolts 5, occupying the top and bottom portions of the casing, are adapted to swing from locking positions (Fig. 2) in which they are substantially horizontal and 95 parallel to unlocking positions (Figs. 3 and 5), in which they are slightly divergent. Said bolts pass through slots 6 in the face plate 2, sufficiently vertically elongated to afford the desired angular travel of the bolts, and 100

the forward ends of the latter are adapted, when the door is closed, to engage in angular slots 7 in a keeper plate 8 to effect locking. Said plate is so secured to the door frame 9 as to occupy a transverse relation to the bolts 5 when the door is closed, or substantially so. The slots 7, as best appear in Fig. 1, have entrance portions interrupting a vertical edge of the plate 8, and bolt-retaining portions extending toward each other from said entrance portions. That edge of the plate 8 encountered by the bolts as the door is closed is beveled, as indicated at 10, to guide the bolts into said entrance portions.

15 In order that the bolts may not be disengaged from the slots 7, by jimmying the door away from the keeper plate, the bolts are preferably terminally formed with enlarged heads 11 engageable behind the keeper plate, as best appears in Fig. 2.

20 The rear ends of the bolts are pivoted upon pins 12, rigidly carried by the casing, and each further pivotally mounting a bell crank lever 13, 14, preferably a sheet-metal stamping. The arms 13 of the two bell cranks underlie the bolts 5, and the arms 14 project toward each other, one slightly overlapping the other, and the latter having a finger 15 projecting toward the face plate.

25 The arms 13 are each formed with a flange 16 bent to lie adjacent to the inner face of the corresponding bolt, and a coiled spring 17 extends from each flange 16 through a slot 18 of the corresponding bolt to the marginal wall 35 of the casing, tending to rock the bell cranks and bolts in unison and thereby establish the unlocked positions of the bolts (Fig. 5).

30 A pair of coiled springs 19 further connect each flange 16 to the bent end 20 of a plate 21 rigidly secured to each bolt and projecting upwardly and downwardly from the same. The function of the springs 19 is to yieldably resist unlocking travel of the bolts, relative to the arms 14 and to return the bolts, after any such travel to their locking positions, when relieved of manual actuating effort.

35 Midway between the two bolts, there is journaled in the fixed side wall of the casing a bushing 22, integrally or otherwise rigidly carrying a toothed wheel 23 interiorly adjacent to said side wall. Upon said bushing, adjacent to said wheel, is journaled a plurality of coaxial tumbler disks, four thereof being 40 employed in the illustrated construction and being designated respectively 24, 25, 26, and 27.

45 The disk 24 turns in unison with said bushing by virtue of a pin 28 fixed in said disk and projecting at one side of the disk for selective engagement in circumferentially spaced apertures 29 in the wheel 23. Said pin also projects at the other side of said disk to engage in arcuate slots 30 formed in the disks 25, 26 and 27, and differing in cir-

cumferential extent. (See Fig. 8.) The tumblers 25, 26 and 27 are further each formed with a marginal notch 31, said notches being registerable with each other and with the finger 15 in certain rotational positions of said tumblers to permit actuation of the bell cranks 13, 14 by the springs 17 to the positions shown in Fig. 5. In undergoing such travel, the bell cranks carry the bolts 5 to their divergent or unlocking positions, which likewise appear in Fig. 5. The disk 24 has a minor portion of its periphery of a re-entrant cam form, as indicated at 32, said portion being required to register with the notches and the finger 15 to permit bolt unlocking rocking of the bell cranks. The function of the cam-forming disk 24 is primarily to shift the finger 15 clear of the notches 31, preliminary to a shifting of the remaining tumblers from their set positions.

50 The bushing 22 is keyed as indicated at 33 upon the cylindrical stem 34 of a tumbler-actuating knob 35. Said stem extends through the casing 1 and door 2a, carrying said knob adjacent to the outer face of the door, as best appears in Fig. 4.

55 A vertically elongated escutcheon plate 36 is secured by screws 37 or the like to the outer face of the door between the latter and said knob, the lower portion of said plate preferably carrying a handle 38 of any suitable design for opening and closing the door. Formed in the plate 36 behind the knob 35 is a short slot 39 arced about the axis of the knob and having a radial end 39a, its other end being preferably rounded and beveled, as best appears in Figure 14, between the front and rear faces of said plate. Slidable upon and surrounding said knob is a ring 40 normally urged by a plurality of coiled springs 41 against an abutment plate 42 carried by and laterally projecting from the outer end of the knob. Said ring is splined on the knob as indicated at 43, insuring rotation in unison of the knob and ring. Rigidly secured to said ring, and projecting toward the plate 36 is a pin 44 which through rotation of the knob and ring is registerable with the slot 39 and by an inward actuation of the ring may be entered in said slot, as shown in Figure 11. Said pin at its inner end has a face planed radially to the axis of the knob, adapted to abut the end 39a of the slot 39 to definitely limit clockwise rotation of the knob when said pin is entered in said slot, the initial position for setting the tumblers being thus established.

60 Between the adjacent tumbler disks 24, 25, 26 and 27 are interposed spacer plates 45 of thin sheet metal, preventing frictional actuation of one tumbler by another. Said plates are preferably of the form best illustrated in Figure 9, having arcuate arms for engagement between the tumblers, the ends of said arms being spaced in such permanent regis-

tration with the finger 15 as to afford the latter free travel toward the tumblers. Said spacer plates are maintained in their positions of use through their engagement with a 5 pair of pins 46 projecting rigidly from the fixed side wall of the casing.

The teeth of the wheel 23 are engaged by the free end of a spring arm 47, best shown in Figure 10, the other end of which is anchored to the casing at 48. Thus there is produced a series of clicks when the wheel 23 is actuated, affording measurement by ear of the angular advance of the knob 35 in either direction.

15 The stem 34 projects beyond the inner face of the door 2a and has sleeved upon this projecting portion the tubular stem 49 of an inside door handle 50. The latter is formed in its back face with a central cavity 51 into 20 which the stem 34 terminally projects, disengagement of the two stems being prevented by a pin 52 carried by said stem in said cavity. This arrangement, it will be noted, permits free relative rotation of the stems 34 25 and 49.

The stem 49 has upon its inner end a diametral tongue 53 which, in the position of use of said stem, fits into a diametral slot 54 in a collar 55 freely journaled in the stem 34 30 and carrying a cam 56 of approximate T-shape.

Upon rocking of the handle 50 in either direction, the cam 56 engages the inner ends of the plates 21, shifting both bolts to their 35 unlocking positions, as best appears in Figure 3. The bell cranks 13, 14 do not participate in this travel of the bolts, being held stationary by engagement of the finger 15 with the edges of the tumbler disks. Upon release of 40 the handle 50, the coiled springs 19 retract said bolts to their normal parallel relation. Between the tumblers and the cam 56 there is preferably interposed a sheet metal plate 57 held from rotation by the pins 46. Said plate 45 engages the stem 34 and bears against the inner end of the bushing 22, thus protecting the tumblers against any disturbance by actuation of the cam 56.

An escutcheon plate 58 is applied to the 50 interior face of the door surrounding the stem 49, and preferably a sleeve 59 is integrated with said plate to journal and conceal the stem 49.

The slots 6 of the face plate 2 are preferably safeguarded to prevent tampering with the lock mechanism by an implement inserted through said slots. Thus, a pair of slide plates 60, mounted interiorly adjacent to the face plate 2, are apertured to accommodate 55 the bolts 5, said slide plates being suitably held against the face plate and moving with the bolts in their rocking travel.

In use of the described lock, when the inside handle 50 is turned, the sleeve 59 turns 60 therewith, and through its tongue and slot

connection to the collar 55 rocks the T-shaped cam 56. The forward end of the latter thereby exerts a direct outward thrust upon one of the plates 21, and the rear end of said cam engages and thrusts outward the plate 20 carried by the other bolt, the position then assumed by the parts being exemplified in Figure 3. During such operation, the two bell crank levers 13, 14 maintain their normal positions, being held from movement by the tumbler disks bearing against the finger 15. The springs 19 are tensioned through such actuation of the bolts, and on release of the inside handle return the bolts to locking positions.

To open the door from the outside, the knob 35 is initially rotated clockwise, inward pressure being at the same time applied to the ring 40. The pin 44 enters the slot 39, upon registration with the latter, and its plane face then encounters the radial end 39a of said slot, establishing the initial tumbler-setting position. The operator now relieves pressure on the ring 40, which responsive to the springs 41 disengages the pin 44 from the slot 39. The knob 35 is now rocked back and forth predetermined distances, as is well known in the art, the desired angular advances being, however, determined entirely by the clicks produced by the teeth of the wheel 23 in escaping past the spring 47. This rocking of the knob first acts through the pin 28 on the tumbler 27 (which has the longest arcuate slot 30) to register the notch 31 of said tumbler with the finger 15. A reverse 100 angular advance of the knob 35 then actuates the tumbler 26 to similarly register its notch 31 with said finger. A further reversal in the direction of actuation of the knob 35 similarly brings the notch 31 of the tumbler 25 into proper position, and a finally reversed actuation of said knob registers the reentrant cam portion of the disk 24 with the previously registered notches. Immediately thereupon, the spring 17 takes effect upon the two bell crank levers to shift the same as appears in Figure 5, and the flanges 16 of said levers cause the bolts 5 to travel in unison with the lever arms 13. Thus, it is seen that retraction of the bolts through manipulation 115 of the tumblers is completely automatic, involving no operation additional to such manipulation.

Thus, it is apparent that the illustrated embodiment of my invention is well calculated to adequately fulfill the objects and advantages primarily stated; it is to be understood that the invention is susceptible to variation, modification and change within the spirit and scope of the subjoined claims.

Having described my invention, what I claim is:

1. In a combination lock, a casing, a bolt pivoted in and projecting from said casing, a keeper plate formed with a marginal

ly opening entrance portion for said bolt and with a bolt retaining portion elongated transversely to said entrance portion, spring means urging said bolt angularly toward registration with said entrance portion, a plurality of coaxial tumblers journaled in said casing and resisting response of the bolt to said spring means, and means for setting said tumblers comprising an actuating element exterior to said casing.

2. In a combination lock, a casing, a bolt journaled in and projecting from said casing, a bell crank lever copivotal with said bolt, having a flange on one of its arms projecting along side of said bolt, and terminally carrying upon its other arm a finger projecting transversely to said arm, a spring acting on said flange tending to rock said bell crank in a direction to shift said bolt to an unlocking position, a plurality of tumblers coaxially pivoted in said casing and normally peripherally engaged by said finger to obstruct response of said bell crank to said spring, said tumblers having notches registrable with each other and with said finger to allow response of the bell crank to the spring, and means for setting said tumblers comprising an actuating element disposed exteriorly of said casing.

3. In a combination lock, a casing, a bolt pivoted in said casing, and projecting therefrom, a member co-pivotal with said bolt between the bolt and a side wall of the casing, and formed with a flange projecting transversely to said side wall for actuating the bolt to an unlocking position through the pivotal travel of said member, a spring acting on said flange to establish the unlocking position of the bolt, a plurality of tumblers normally peripherally engaging said flanged member to resist its response to said spring and registrable with each other in a certain position to permit such response, and means for setting said tumblers comprising an actuating element disposed exteriorly to said casing.

4. In a combination lock, a casing, a bolt pivoted in and projecting from said casing, a coiled spring acting on said bolt within said casing to establish its unlocking position, a plurality of tumblers normally peripherally opposing travel of said bolt responsive to said spring, and registrable with each other in a certain position to permit such travel, means for setting said tumblers comprising an actuating element disposed exteriorly to said casing at one side thereof, and means for actuating said bolt independently of said tumblers accessible from the other side of said casing.

5. In a combination lock, a casing, a pair of bolts pivoted in and terminally projecting from said casing, means yieldably urging said bolts angularly to unlocking positions, a plurality of coaxial tumblers resisting response

of both said bolts to said means, a cam journaled coaxially with said tumblers, rotatively effective upon said bolts to establish their unlocking positions independently of said tumblers, actuating means for said cam carried by said casing exteriorly of and at one side of the casing, and means for setting said tumblers carried by said casing exteriorly of and at the other side of said casing.

6. In a combination lock, a casing, a pair of bolts spaced apart within said casing and pivotally movable to and from each other, a pair of members, each copivotal with one of said bolts, said members being effective on said bolts to move them from each other, means yieldably urging said members in a direction to effect movement of the bolts from each other, a plurality of coaxial tumblers adapted to restrain said members from response to said urging means, means actuatable from one side of said casing for setting said tumblers in non-restraining positions, and means actuatable from the other side of said casing for moving said bolts apart, independently of said members copivotal with the bolts.

7. In a lock, the combination with a door and its frame, of a headed bolt pivoted upon the door for up and down swinging movement, a keeper plate upon the door frame, formed with a slot opening edgewise of said plate to admit said bolt, as the door is closed, said slot having a substantially vertical extension to receive the bolt in its locking position, the bolt head in said position restraining the bolt from withdrawal from the plate in a direction transverse to said plate.

In testimony whereof I sign this specification.
